UNITED STATES PATENT OFFICE.

BYRON B. GOLDSMITH, OF NEW YORK, N. Y.

DESIGN FOR A TELESCOPING COVER FOR PACKING AND DISPLAY BOXES.

SPECIFICATION forming part of Design No. 35,514, dated December 31, 1901.

Application filed October 10, 1901. Serial No. 78,282. Term of patent 14 years.

To all whom it may concern:

Be it known that I, BYRON B. GOLDSMITH, a citizen of the United States, and a resident of the city, county, and State of New York, have invented a new and original Design for a Telescoping Cover for a Packing and Display Box, of which the following is a specification.

The drawing represents the cover of the box in perspective.

The leading feature of the design consists in a telescopic cover A, having a band B at one end carrying an ornamentation in the shape of a frame surrounding a space, usable for an advertisement, and a band D at the end removed from the band B, also carrying an or-

namentation in the shape of a frame, but having the part within the frame cut away and removed, so as to show the part of the article displayed, which is found underneath. 20

What I claim is—

The design for a telescoping cover for a packing and displaying box for lead-pencils and similar articles substantially as herein shown and described. 25

In testimony whereof I have signed my name to this specification in the presence of two subscribing witnesses.

BYRON B. GOLDSMITH.
